COMBINED DISPENSER AND CLOSURE FOR
A CONTAINERMaurice Goldman, Los Angeles, Calif., assignor to
Dispensers, Inc., Los Angeles, Calif., a corpora-
tion of California

Application June 30, 1950, Serial No. 10,912

Term of patent 14 years

(Cl. D58—26)

To all whom it may concern:

Be it known that I, Maurice Goldman, a citizen of the United States, residing at Los Angeles, in the county of Los Angeles and State of California, have invented a new, original, and ornamental Design for a Combined Dispenser and Closure for a Container, of which the following is a specification, reference being had to the accompanying drawing, forming a part thereof, in which:

Fig. 1 is a perspective view of a combined dispenser and closure for a container, showing my new design;

Fig. 2 is a top plan view thereof;

Fig. 3 is a side elevational view thereof;

Fig. 4 is a front elevational view thereof;

Fig. 5 is a bottom view thereof; and,

Fig. 6 is a rear elevational view thereof.

I claim:

The ornamental design for a combined dispenser and closure for a container, substantially as shown.

MAURICE GOLDMAN.
